Primary Examiner—Catherine Tuttle(74) *Attorney, Agent, or Firm*—Cislo & Thomas LLP**CLAIM**

I claim the ornamental design for a snail novelty, as shown and described herein.

DESCRIPTION

FIG. 1 is a left side elevational view showing my new design;

FIG. 2 is a front view thereof;

FIG. 3 is a top plan view thereof;

FIG. 4 is a rear view thereof;

FIG. 5 is a right side view thereof; and,

FIG. 6 is a bottom view thereof.

The portions shown in broken lines are for illustrative purposes only; and form no part of the claimed design.
